PUNCH

William J. Ehksam, Enterprise, Kans., assignor to
 The J. B. Ehksam & Sons Manufacturing Company, Enterprise, Kans., a corporation of Kansas

Application August 8, 1938, Serial No. 223,641

10 Claims. (Cl. 164—85)

The present application relates to a punch and a die for cooperation therewith; and more specifically to a punch and die particularly adapted for use in perforating unset plaster board.

5 A great deal of perforated plaster board, commonly known as plaster lath, is used in building, as a substituted for wood or metal lath; and it has been found that it is desirable, if not absolutely necessary, to form such plaster board with 10 perforations, of suitable size and spacing, through which the plaster protrudes to form anchorages whereby the plaster is held in place. Such board is customarily formed by spreading a plastic material, usually having a plaster of Paris base, 15 between two layers of paper, or the like; and allowing the plastic to set. In the prior commercial art, it has been customary to cut the board into sections before the plastic has set, thereafter allowing the plastic to set and then drying the 20 board sections by passing them to and through a dryer in which the excess moisture is removed. After the board has been dried, the boards are stacked into bundles and the desired perforations are customarily formed by gang drills, the drills 25 being driven through the stacks of boards.

This operation results in the deposition of powdered plaster of Paris between the boards of the stack and within irregularities in the surfaces of the perforations, so that, as the perforated 30 boards are used for application to walls or ceilings, the powdered material tends to fall. Furthermore, it has been found in the practical art that, whereas the above-described operation produces clean perforations through some of the 35 boards of the stack, it will form ragged, rough perforations through others, notably the boards toward the middle of the stack.

It is the primary object of the present invention to provide a punch and die of such character as to permit perforation of plaster board before the plastic has become set, to produce clean, smooth perforations, and to eliminate the production of powdered material. It is a further object of the invention to provide such a punch and die in order to make possible perforation of the product before the plastic has set, whereby the drying operation will be facilitated and rendered less expensive. Obviously, if the material is perforated before the plastic has been dried, the 45 drying air will be permitted to come into contact with an enormously increased surface of plastic, whereby the drying and setting step is performed much more rapidly. Although the punch of the present application is primarily intended for use 50 in the manner above described, it will be ob-

vious that many of the advantages resulting from the particular construction of my punch and die will arise no matter with what material they are used.

Heretofore, attempts have been made to perforate plaster board by punching prior to the setting of the plastic, but such attempts have, to the best of my knowledge, invariably resulted in failure. Numerous patents have been granted upon machines including punches carried by rotating 10 elements driven at a lineal speed equivalent to the speed of movement of the board in the forming machine; but in practical operation, it was found that such punches invariably produced ragged, 15 imperfect perforations. It is my opinion that the failure of such machines was due in part to an incorrect theory as to the proper method of operation, and in part to the fact that the punches and dies used in such prior art machines were 20 improperly formed to perform the desired functions in a satisfactory manner.

Further objects of the invention will appear as the description proceeds. To the accomplishment of the above and related objects, my invention may be embodied in the forms illustrated in the 25 accompanying drawing, attention being called to the fact, however, that the drawing is illustrative only, and that change may be made in the specific constructions illustrated and described, so long as the scope of the appended claims is not violated. 30

Fig. 1 is an elevation of a punch constructed in accordance with the present invention, parts being broken away for clarity of illustration;

Fig. 2 is an elevation of one form of die which may desirably be used in conjunction with such 35 punch;

Fig. 3 is a fragmental sectional view of the 40 punching machine, showing my punch and another form of die incorporated in the machine; and

Fig. 4 is a view similar to Fig. 3; but illustrating a different position of the elements, and showing still another form of die.

Referring more particularly to Fig. 1, it will be seen that the punch 10 comprises a cylindrical 45 shank 11, an enlarged portion 12, merging with said shank through a tapered shoulder 13, and a further enlarged portion 14 merging with the portion 12 through a tapered shoulder 15.

In the leading end of the shank 11 is formed a 50 substantially hemispherical cavity 16, the depth of which, in an axial direction, is substantially equal to the diameter of the shank 11. A perimetral series of teeth 17 is arranged about the mouth of the cavity 16, said teeth being, as is 55

clearly shown in Fig. 1, in elevation, shaped substantially as isosceles triangles. The equal sides 18 of such triangle are sharpened to cutting edges; and, as is further shown in Fig. 1, each tooth decreases progressively in radial thickness from its base 19 to sharpness at its apex 20. Thus, when the punch is advanced into a board, the apices 20 of the teeth 17 prick into the material like needles, and thereafter the sharpened edges 18 slice through the material like knives with a shearing action. The portion of the material punched out by the punch is received within the cavity 16, and is carried through the material and through the cooperative die. A port 21 opens 10 from the base of the cavity 16 through the trailing end 22 of the punch.

While I have stated that the shank 11 of the punch 10 is cylindrical, it will be obvious that it may be of any desired cross sectional shape. 20 While I have further stated that the cavity 16 is substantially hemispherical, it will likewise be obvious that that shape is not essential. The essentials of the cavity are that it shall be so shaped that the inner surfaces of the teeth 17 shall merge smoothly with the walls of the cavity, that the depth of the cavity, in the direction of the axis of the shank, shall be not materially less than the thickness of the board to be perforated, and that the volume of the cavity, preferably 25 measured from the roots of the teeth, shall be at least sufficient to accommodate the slug punched from a single thickness of board. There is, of course, no maximum limit to the depth of the cavity. I believe that it might be possible to continue the cavity, upon its maximum diameter, through the length of the punch, whereby slugs punched from the board material would collect and move progressively upwardly through the punch, ultimately being discharged from the 30 upper end thereof. In that case, of course, the header 23, hereafter to be described, would not be necessary. I prefer, however, the illustrated structure; since it is possible that the slugs punched from the board material and retained 35 within the punch, in the manner just described, might plug the punch passage upon setting, to cause considerable trouble.

As is more particularly shown in Fig. 3, the punch is carried by a reciprocable head H with 50 which is associated a header 23 which is connected to a suitable source of compressed air. The head H carries a spud 24 formed with a port 25 providing communication between the header 23 and the port 21; and the punch 10 is affixed 55 to the spud through the medium of a coupling 26. Thus, when the perforation has been formed, compressed air will be supplied to the header 23 to flow through the passages 25 and 21 to expel the retained slug of material cut from the board 60 and retained in the cavity 16.

A table 27 associated with the head H is formed with a socket 28 for the reception of the flange 29 of a die 30, said die being secured in place on the table by a nut 31, or the like. The die 30 is 65 formed with an opening 32 adapted to receive the shank 11 of the punch 10 with a working fit; said opening 32 communicating with an enlarged passage 33 extending entirely through the die 30.

Preferably, a stripper plate 34, formed with a 70 port 35 therein, is associated with the other elements of the punching mechanism to prevent the board, indicated generally by the reference numeral 36, from being lifted away from the table 27 upon return movement of the punch. As is 75 shown in Fig. 3, the board to be perforated con-

sists of two layers 37 and 38 of paper or other fibrous material holding therebetween a layer 39 of plastic material.

In Fig. 2 is shown another form of die, indicated generally by the reference numeral 30'. The die 30' is formed with an axial opening 32' which is bordered, at the uppermost end of the die, by an upstanding perimetral ridge 40. Said ridge, in cross section, is shaped as a right triangle the base 41 of which lies in the uppermost 10 surface of the die, the altitude 42 of which coincides with the internal surface of the opening 32', and the hypotenuse 43 of which lies in a radial plane of the die. Said ridge 40 is formed with a series of perimetally spaced, axially extending, substantially V-shaped notches 44, and with a second series of perimetally spaced, axially extending, substantially V-shaped notches 45 of less depth, each of the notches 45 being positioned substantially midway between two of the notches 44. For some purposes, I have found the die 30' to be more satisfactory than any other die; partially for the reason that it forms a countersink at that end of the perforation which, during the perforating step, is downwardly presented. That countersink, when it is used at the back of the plaster lath, tends to form a better anchorage for the plaster applied to the opposite surface of the board.

The die 30'' shown in Fig. 4 is identical with the die 30, except for the fact that it is formed with teeth 46 arranged about the mouth of the opening 32''.

At various points in the specification, and in the claims, I have referred to "unset" plaster board or plastic. That term is intended to apply to all conditions of the plastic prior to the final set condition in which the plaster of Paris or other similar material has absorbed the theoretical amount of water of chemical combination. Usually, the perforation will take place at a time subsequent to the initial set and prior to final set. The condition of initial set is that condition in which a depression, indentation, or perforation formed in the plastic will not be refilled by flow 40 of the material.

I claim as my invention:

1. A punch for perforating unset plaster board or the like, comprising a shank formed at its leading end with a perimetral series of teeth, 50 each of said teeth having its external surface flush with the external surface of said shank being substantially triangular in elevation and the thickness thereof being progressively reduced from the base of the triangle to the apex 55 thereof.

2. A punch for perforating unset plaster board or the like, comprising a shank formed at its leading end with a perimetral series of teeth, each of said teeth being shaped, in elevation, 60 substantially as an isosceles triangle, the equal sides thereof being sharpened to cutting edges, and the thickness of each tooth being progressively reduced from its inner surface outwardly from the base of the triangle to sharpness at the apex 65 thereof.

3. The combination with a punch formed at its leading end with a cavity and provided with a perimetral series of teeth arranged about the mouth of said cavity, of a die formed with an 70 opening adapted to receive said punch with a working clearance and communicating with an enlarged passage extending entirely through said die.

4. The combination with a punch formed at 75

- its leading end with a cavity and provided with a perimetral series of teeth arranged about the mouth of said cavity and provided with a port leading from said cavity through the trailing end of said punch, of a die formed with an opening adapted to receive said punch with a working clearance and communicating with an enlarged passage extending entirely through said die.
5. The combination with a punch formed at its leading end with a cavity and provided with a perimetral series of teeth arranged about the mouth of said cavity, of a die formed with an opening adapted to receive said punch with a working clearance, said die being provided with a perimetral series of teeth arranged about said opening and presented toward said punch.
6. The combination with a punch formed at its leading end with a cavity and provided with a perimetral series of teeth arranged about the mouth of said cavity, of a die formed with an opening adapted to receive said punch with a working clearance, said die being provided with a perimetral series of teeth arranged about said opening and presented toward said punch, the teeth of said die having axial and perimetral dimensions less than those of the teeth on said punch.
7. The combination with a punch formed at its leading end with a cavity and provided with a perimetral series of teeth arranged about the mouth of said cavity, of a die formed with an opening adapted to receive said punch with a working clearance, and an axially extending perimetral ridge closely surrounding the mouth of said opening and projecting toward said punch, said ridge being formed, in cross section, substantially as a right triangle with its base disposed in the uppermost surface of said die, its altitude coinciding with the internal surface of said opening, and its hypotenuse lying in a radial plane of said die, the uppermost surface of said ridge, lying in the apex of such triangle, being formed with a series of perimetral spaced, axially extending, substantially V-shaped notches and with a second series of perimetral spaced, axially extending, substantially V-shaped notches of less axial depth, each notch of said second series being positioned substantially midway between two adjacent notches of said first series.
9. A punch for perforating unset plaster board or the like, comprising a cylindrical shank formed, at its leading end, with a substantially hemispherical cavity, the volume of said cavity being at least equal to the volume of a piece of the material to be operated upon having a thickness equal to the thickness of such material and a cross sectional area equal to the cross sectional area of the mouth of said cavity, the mouth of said cavity being supplied with a perimetral series of teeth, each of said teeth having its entire outer surface flush with the outer surface of said shank, and its inner surface progressively flaring upon the arc of a circle from the extremity of the tooth toward its root.
10. A punch for perforating unset plaster board or the like, comprising a cylindrical shank formed, at its leading end, with a substantially hemispherical cavity, and a perimetral series of teeth arranged about the mouth of said cavity, each of said teeth having its entire outer surface flush with the outer surface of said shank, and its inner surface progressively flaring upon the arc of a circle from the extremity of the tooth toward its root.
15. The combination with a punch formed at its leading end with a cavity and provided with a perimetral series of teeth arranged about the mouth of said cavity, of a die formed with an opening adapted to receive said punch with a working clearance, said die being provided with a perimetral series of teeth arranged about said opening and presented toward said punch.
20. The combination with a punch formed at its leading end with a cavity and provided with a perimetral series of teeth arranged about the mouth of said cavity, of a die formed with an opening adapted to receive said punch with a working clearance, said die being provided with a perimetral series of teeth arranged about said opening and presented toward said punch, the teeth of said die having axial and perimetral dimensions less than those of the teeth on said punch.
25. The combination with a punch formed at its leading end with a cavity and provided with a perimetral series of teeth arranged about the mouth of said cavity, of a die formed with an opening adapted to receive said punch with a working clearance, and an axially extending perimetral ridge closely surrounding the mouth of said opening and projecting toward said punch, said ridge being formed, in cross section, substantially as a right triangle with its base disposed in the uppermost surface of said die, its altitude coinciding with the internal surface of said opening, and its hypotenuse lying in a radial plane of said die, the uppermost surface of said ridge, lying in the apex of such triangle, being formed with a series of perimetral spaced, axially extending, substantially V-shaped notches and with a second series of perimetral spaced, axially extending, substantially V-shaped notches of less axial depth, each notch of said second series being positioned substantially midway between two adjacent notches of said first series.
30. A punch for perforating unset plaster board or the like, comprising a cylindrical shank formed, at its leading end, with a substantially hemispherical cavity, the volume of said cavity being at least equal to the volume of a piece of the material to be operated upon having a thickness equal to the thickness of such material and a cross sectional area equal to the cross sectional area of the mouth of said cavity, the mouth of said cavity being supplied with a perimetral series of teeth, each of said teeth having its entire outer surface flush with the outer surface of said shank, and its inner surface progressively flaring upon the arc of a circle from the extremity of the tooth toward its root.
35. A punch for perforating unset plaster board or the like, comprising a cylindrical shank formed, at its leading end, with a substantially hemispherical cavity, and a perimetral series of teeth arranged about the mouth of said cavity, each of said teeth having its entire outer surface flush with the outer surface of said shank, and its inner surface progressively flaring upon the arc of a circle from the extremity of the tooth toward its root.
40. The combination with a punch formed at its leading end with a cavity and provided with a perimetral series of teeth arranged about the mouth of said cavity, of a die formed with an opening adapted to receive said punch with a working clearance, said die being provided with a perimetral series of teeth arranged about said opening and presented toward said punch.
45. The combination with a punch formed at its leading end with a cavity and provided with a perimetral series of teeth arranged about the mouth of said cavity, of a die formed with an opening adapted to receive said punch with a working clearance, said die being provided with a perimetral series of teeth arranged about said opening and presented toward said punch.

WILLIAM J. EHRSAM.
